US0D1089524S

(12) **United States Design Patent** (10) **Patent No.:** **US D1,089,524 S**
(45) **Date of Patent:** **** Aug. 19, 2025**

(54) **PORTABLE WATER TREATMENT DEVICE**

(71) Applicant: **Blu Technology LLC**, Kalamazoo, MI (US)

(72) Inventors: **Corbin Collet**, Portage, MI (US); **Brian Brandon**, Bellevue, MI (US)

(73) Assignee: **Blu Technology LLC**, Portage, MI (US)

(**) Term: **15 Years**

(21) Appl. No.: **29/947,364**

(22) Filed: **Jun. 14, 2024**

Related U.S. Application Data

(63) Continuation of application No. 29/877,191, filed on Jun. 2, 2023, now Pat. No. Des. 1,043,906, which is a continuation of application No. 17/847,855, filed on Jun. 23, 2022.

CLAIM

The ornamental design for a portable water treatment device as shown and described.

DESCRIPTION

FIG. 1 is a front, perspective view of a portable water treatment device showing our new design;

FIG. 2 is a right side elevation thereof;

FIG. 3 is a left side elevation thereof;

FIG. 4 is a front elevation view thereof;

FIG. 5 is a rear elevation view thereof;

FIG. 6 is a top, plan view thereof; and,

FIG. 7 is a rear, perspective view thereof.

FIGS. 1-7 show portions of the portable water treatment device in dash-dot broken lines. The dash-dot broken lines illustrate portions of the portable water treatment device that form no part of the claimed design.

1 Claim, 5 Drawing Sheets
